UNITED STATES PATENT OFFICE.

JOSHUA P. EATON, OF WOBURN, MASSACHUSETTS.

DESIGN FOR A SHOE-PATTERN.

SPECIFICATION forming part of Design No. 20,953, dated July 21, 1891.

Application filed June 25, 1891. Serial No. 397,529. Term of patent 14 years.

To all whom it may concern:

Be it known that I, JOSHUA P. EATON, of Woburn, county of Middlesex, State of Massachusetts, have invented and produced a new and original Design for Shoe - Patterns, of which the following is a specification, reference being had to the accompanying drawing, forming part thereof.

The drawing shows in plan view a shoe-pattern, showing my design.

a represents the vamp or toe portion; *b*, a part of the inside shank or quarter-piece; *c*, the complete outside shank or quarter-piece; *d*, a part of the inside shank or quarter-piece, *e*, a front top of sufficient width and length,

and *f* the back top, also of sufficient width and length.

This pattern is adapted to be folded or crimped on the dotted lines *g h*.

I claim—

The design for a shoe-pattern, substantially as herein shown and described.

In testimony whereof I have signed my name to this specification in the presence of two subscribing witnesses.

JOSHUA P. EATON.
